T. B. DRAPER,
COMBINED COUCH AND CRIB.

APPLICATION FILED OCT. 22, 1917. RENEWED JUNE 12, 1920.

1,366,906.

Patented Feb. 1, 1921.

UNITED STATES PATENT OFFICE.

THOMAS B. DRAPER, OF DETROIT, MICHIGAN.

COMBINED COUCH AND CRIB.

1,366,906.

Specification of Letters Patent.

Patented Feb. 1, 1921.

Application filed October 22, 1917, Serial No. 197,777. Renewed June 12, 1920. Serial No. 388,687.

To all whom it may concern:

Be it known that I, THOMAS B. DRAPER, a subject of the King of Great Britain, residing at Detroit, in the county of Wayne 5 and State of Michigan, have invented certain new and useful Improvements in Combined Couches and Cribs, of which the following is a specification, reference being had therein to the accompanying drawings.

10 This invention relates to a combined couch and crib, and the primary object of my invention is to provide a couch in a portion of which a crib, cot or other structure may be concealed while another portion of the couch 15 may be used as a chest or compartment for clothes or other matter.

Another object of my invention is to furnish a couch with a concealed crib or bed structure that may be easily and quickly 20 withdrawn to an active useful position, the operation of withdrawing the crib causing the parts thereof to assume supporting positions so that the crib or bed structure is ready for use.

25 A further object of my invention is to provide a piece of furniture of the above class wherein the parts are constructed with a view of reducing the cost of manufacture and at the same time retain those features 30 by which safety, durability and ease of assembling are secured. With such ends in view, my invention resides in the novel construction, combination and arrangement of parts to be hereinafter more fully described 35 and then claimed.

Reference will now be had to the drawings, wherein—

Figure 1 is a side elevation of the couch, partly broken away and partly in section, 40 showing by dotted lines the crib as partially placed in the couch;

Fig. 2 is a cross sectional view taken on the line II—II of Fig. 1;

Fig. 3 is a side elevation of the crib in 45 an active position, with the side rails thereof raised;

Fig. 4 is an end view of the same;

Fig. 5 is a side elevation of a portion of the crib, partly broken away and partly in 50 section, showing the side rails thereof lowered;

Fig. 6 is a detail sectional view of a portion of the crib illustrating one of the latches thereof, and

55 Fig. 7 is a perspective view of a detached latch.

The couch comprises an oblong box like

structure having a bottom wall 1 supported by suitable legs 2, fixed longitudinal walls 3, a fixed end wall 4, and a transverse partition 5. The transverse partition 5 is contiguous to one end of the couch and is connected by longitudinal partitions 7 to the end wall 4, said longitudinal partitions being adjacent the side walls 3 so as to provide 60 side compartments or pockets 8, and a large compartment between the partitions 7 in which clothes or other matter may be placed.

The upper edges of the side walls 3, adjacent the transverse partition 5 are provided with bearings 6 and pivotally connected to or fulcrumed on said bearings are arms 9 having the ends thereof in frictional engagement with sector plates 10 in the pockets 8 at the chest end of the couch. 70 The other ends of the arms 9 support a couch top or cushion 11 having an end wall 12 adapted to close the large compartment formed by the side walls 3, bottom wall 1 and partition 5. The couch top may be 80 of any conventional form, for instance as shown in Fig. 2, and may be raised and held in adjusted position through the medium of the arms 9 engaging the sector plates 10, said sector plates also constituting 85 means for preventing a sudden lowering movement of the couch top.

A cover or cushion 13 is adapted to close the small compartment of the couch and aline with the couch top 11, when closed. 90

In the large compartment of the couch is a crib frame 14 adapted for supporting a suitable spring 15. The outer end of the crib frame 14 rests upon anti-frictional rollers 16 adjacent the end wall 12, and when 95 the couch top is raised, the crib frame 14 may be pulled outwardly on said rollers. The lower edges of the crib frame, adjacent the inner end thereof, are provided with strap hinges 17 connected to a head or foot 100 piece 18 having casters 19.

Connected to the upper edges of the frame 14, adjacent the outer end thereof, and by strap hinges 20 is a head or foot piece 21 having casters 22. With the couch top 105 raised, the piece 21 may be gripped to pull the crib frame 14 outwardly and in so doing the piece 21 is swung to an active position, that is, from a horizontal position to substantially a vertical position at right angles 110 to the outer end of the crib frame 14. As the crib frame is pulled outwardly, the casters 19 of the piece 18 impinge against the rollers 16, which serve as temporary stops, causing

the piece 18 to pivot on its casters and be swung to a vertical position at right angles to the inner end of the crib frame 14. In such position the crib can be further moved 5 from its compartment of the couch.

Connected to the inner longitudinal side walls of the frame 14 by double strap hinges 23 are side rails 24 of any desired design. The side rails 24 are swung inwardly one 10 upon the other, as shown in Fig. 2, when the crib is housed within the couch, but said side rails may be raised to a vertical position on the frame 14, as shown in Figs. 3 and 4, or may be lowered at the outer sides 15 of the frame as shown in Fig. 5.

It is necessary to use a plurality of latches in connection with the crib structure and at the ends of the crib frame 14 are snap latches 25 adapted to engage in keeper plates 26 carried by the head or foot pieces 18 and 21 of the crib, these latches constituting means for maintaining the head and foot pieces in active vertical positions, thus preventing accidental collapse of the crib while in use.

25 The upper ends of the head or foot pieces 18 and 21 are also provided with latches to receive the ends of the side rails 24 and maintain said rails in a vertical position on the frame 14 as shown in Fig. 3. These 30 latches are in the form of face plates 27 mounted over recesses 28 in the pieces 18 and 21. Each face plate has opposed pivoted beveled spring pressed latch members 29 held normally extended by a spring 30 mounted in the recess 28, said latch members permitting of the side rails 24 being swung into engagement therewith from either side, and either latch member may be manually depressed to release the side rail and permit 40 of it being lowered at either side of its supporting wall.

The face plate has the lower edge thereof provided with an angled keeper 31, to receive a hook shaped member 32 carried by 45 the end of the side frame 24, said member and keeper preventing the upper end of either piece 18 or 21 from swinging outwardly, thus coöoperating with the latches 25 in preventing collapse of the crib structure.

50 In some instances, the head or foot pieces 18 and 21 may be provided with latches engaged by the ends of the side rails 24 to hold said rails in lowered positions at the outer sides of the crib frame 14.

55 What I claim is:—

1. A combined couch and crib comprising a boxlike structure having a large compartment and a small compartment, a cover for the small compartment of said structure, a top pivoted on said structure with the large compartment thereof, means in the small compartment of said structure and at the sides thereof for holding said top in adjusted position, and a collapsible crib structure housed within the large compartment.

of said structure and adapted to be withdrawn therefrom when said top is raised.

2. A combined couch and crib embodying a boxlike structure having a pivoted top adapted to be raised, means in said structure 70 for holding said top in a raised position, a collapsible crib in said structure adapted to be withdrawn therefrom when said top is raised and comprising a frame, and head and foot pieces connected thereto and 75 brought into active position by the withdrawal of said frame from said structure.

3. A combined couch and crib embodying a boxlike structure having a pivoted top adapted to be raised, a collapsible crib in 80 said structure adapted to be withdrawn therefrom when said top is raised, said crib comprising a frame, head and foot pieces connected thereto and adapted to be brought to active positions when said frame is withdrawn from said structure, and side rails connected to said frame and adapted to be connected to said head and foot pieces.

4. A combined couch and crib embodying a boxlike structure having large and small 90 compartments, a cover for the small compartment of said structure, a top for the large compartment of said structure, and a collapsible crib in the large compartment of said structure having head and foot pieces 95 brought to active positions when said crib is withdrawn from said structure.

5. A combined couch and crib embodying a boxlike structure having a large compartment and side pockets, a pivoted top for the 100 large compartment of said structure, means in the side pockets of said structure adapted to hold said top in adjusted position, and a collapsible crib in the large compartment of said structure adapted to be withdrawn 105 therefrom and assume an active position by such withdrawal.

6. A crib comprising a frame, head and foot pieces connected thereto above and below said frame and adapted to assume active 110 positions at the ends of said frame, means adapted for holding said head and foot pieces in active positions relative to said frame, and means adapted to inclose said crib when collapsed.

7. A collapsible crib comprising a frame, head and foot pieces connected to the upper and lower sides of said frame and normally parallel therewith and adapted to be swung to active positions at the ends of said frame, 120 side rails connected to said frame and capable of being raised and lowered relatively to said frame, and means adapted to inclose said crib when collapsed.

In testimony whereof I affix my signature 125 in the presence of two witnesses.

THOMAS B. DRAPER.
